RAILWAY TRUCK

Percy B. Camp, Maywood, Ill., assignor to Cardwell Westinghouse Company, a corporation of Delaware

Application December 31, 1934, Serial No. 759,827

12 Claims. (CL 105—193)

The invention relates to railway trucks provided with springs for supporting the truck bolster, and supplemental mechanism for augmenting the resistance to the downward movement of the bolster.

The object of the invention is to provide simple but highly efficient friction mechanism for supplementing the spring resistance.

Two forms of the invention are hereinafter described, and are illustrated in the accompanying drawings, in both of which the downward movement of the bolster is resisted in part by friction between the truck frame columns and spring-advanced shoes carried by the bolster, such friction being augmented by stationary wedge means for increasing the compression of the shoe springs as the bolster descends.

In the drawings:

Fig. 1 is a detail elevation of a side frame of a railway truck, the bolster and its supports being shown in section;

Fig. 2 is a detail section on the line 2—2 of Fig. 1;

Fig. 3 is a detail section on the line 3—3 of Fig. 1;

Fig. 4 is a view similar to Fig. 1, showing a modification of the invention;

Figs. 5 and 6 are detail sectional views on the lines 5—5 and 6—6, respectively, of Fig. 1.

One of the side frames of a railway truck is shown, and is provided with the usual top and bottom arch-bar members 10, 11, and columns 12, 13, connecting these arch-bar members and between which is located the truck bolster 14, comprising top and bottom plates 15, 16. The bolster is supported on springs 17, shown as of the helical type, which rest upon the lower arch member 11. These springs may be of any desired number, four being indicated.

That portion of the bolster 14 which is directly between the columns 12, 13, is open at its sides, as plainly indicated in Fig. 1, and these openings are covered by friction shoes 18, 19, which are in channel form, their flanges 20, 21, overlapping and slidably engaging the top and bottom members 15, 16, of the bolster.

A pair of helical springs 22, 23, are interposed one between each of the friction shoes and the inner spring seats 24, 25. The rearward faces of these inner shoes flare downwardly and bear against a wedge element 26, supported by means of a post 27 supported by the lower arch-bar 11. Interposed between the friction shoes 18, 19, and the columns 12, 13, are a pair of friction plates 28, 29, which preferably rest upon the lower arch-

bar 11 and are of channel form, their flanges embracing the columns, as most plainly shown in Fig. 3.

The downward movement of the bolster is at all times resisted by the springs 17, and by the friction developed by the shoes 18, 19, and the plates 28, 29. The frictional resistance is augmented as the bolster moves downwardly by the action of the wedge element 26 in forcing apart the spring seats 24, 25, thus compressing the springs 22, 23, and gradually augmenting the pressure of the friction shoes upon the plates 28, 29. The friction is, of course, gradually diminished upon recoil.

In the construction shown in Figs. 4, 5 and 6, 15 the side frame of the truck and the bolster 14 may be of the same form as in the construction just described. Springs 30, 31, housed within the chamber of the bolster bear outwardly against friction shoes 32, 33, corresponding in form and 20 function with the shoes 18, 19. The springs 30, 31, react against inner spring seats 34, 35, which, when adjusted to service position, are stationary, except as hereinafter pointed out. The inner 25 faces of the columns, as 13, are engaged by the friction shoes and are inclined inwardly and downwardly, to cause a wedging action for increasing the spring pressure on the shoes as the bolster descends. Preferably the columns are 30 faced with upwardly tapering plates 36, 37, of suitable friction-resisting metal (the inner faces 35 of the columns being upright) which overlap their margins, and rest upon the lower arch 11.

A tapering or wedge-shaped adjusting bar 38 is pivoted adjacent the end of the bolster 14, as 35 shown at 39, and projects into the chamber within which the springs 30, 31, are housed, engaging correspondingly inclined surfaces on the rear faces of the spring seats 34, 35. To provide for the adjustment of the spring tension the 40 bar 38 is adapted to be shifted longitudinally by any suitable means. As shown, it is provided with a plurality of longitudinal apertures for receiving the pivot pin 39.

Each of the seats 34, 35, reacts upon the other through the bar 38 without putting the latter under lateral strain, should the pressure for any reason be unequal through the two springs because of the pivotal mounting of the bar. Longitudinal shifting of the bar 38 is provided for to make readjustment possible, as the springs 30, 31, become permanently shortened in service. To this end the bar is provided with an additional pivot hole 40.

In assembling the parts in this construction the bolster is thrust into the lower part of the space between the columns, the springs 30 and 31, inner spring seats and friction shoes being first applied to it, and the plates 36, 37, are now inserted laterally upward and fitted against the columns, the relatively wide spacing of the lower portions of the columns, as shown in Fig. 4, facilitating this operation. The adjusting element 10 38 is now entered. This adjusting element places the springs 30, 31, under initial but slight compression, and resists inward movement of the spring seats 34, 35, as the friction shoes 32, 33, are forced backwardly by the wedging action of 15 the tapering plates 36, 37, as the bolster descends. In action the resistance to downward movement of the bolster is gradually augmented by reason of the tapering form of the plates 36, 37, and is gradually diminished on recoil.

20 In both forms of construction the load is normally supported by the springs 17. Vertical movement of the bolster is steadied by the friction action, the resistance being gradually augmented and diminished, and the objectionable rhythmic movement frequently developed being prevented.

The invention may be differently embodied within the scope of the appended claims.

I claim as my invention—

- 30 1. In a railway truck, in combination, a side frame having a lower arch-bar and columns rising therefrom, a hollow bolster having openings in its side walls, supporting springs for the bolster, friction shoes crossing the openings in the bolster walls, springs urging the shoes against the columns, a pair of spring seats interposed between the last-named springs, and a stationary upstanding spreading wedge interposed between the seats.
- 35 2. In a railway truck, in combination, a side frame having a lower arch-bar, and columns rising therefrom, a hollow bolster located between the columns and having openings in its side walls, a pair of friction shoes carried by the bolster and crossing its side openings, a pair of spring seats mounted within the bolster their adjacent faces flaring downwardly, a spreading wedge projecting upwardly from the lower arch bar and engaging the wedge faces of the seats, springs interposed between the seats and the shoes for urging the latter against the columns, and 40 springs rising from the lower arch-bar and supporting the bolster.
- 45 3. In a railway truck, in combination, a side frame having a lower arch-bar, and columns rising therefrom, a hollow bolster located between the columns and having openings in its side walls, a pair of friction shoes carried by the bolster and crossing its side openings, a pair of spring seats mounted within the bolster their adjacent faces flaring downwardly, a spreading wedge projecting upwardly from the lower arch-bar and engaging the wedge faces of the seats, springs interposed between the seats and the shoes for urging the latter against the columns, friction 50 plates lining the inner faces of the columns, and springs rising from the lower arch-bar and supporting the bolster.
- 55 4. In a railway truck, in combination, a side frame having a lower arch bar and columns rising therefrom, a hollow bolster vertically movable between the columns and having open sides, springs supporting the bolster from the lower arch bar, upwardly tapering friction liners for the inner faces of the columns, friction shoes carried by the bolster and crossing the openings in the side walls of the bolster, a pair of springs urging the shoes against the liners, spring seats for the inner ends of the last-named springs, and a spreading element interposed between the seats.
- 60 5. In a railway truck, in combination, a side frame having a lower arch bar and columns rising therefrom, a hollow bolster vertically movable between the columns and having open sides, springs supporting the bolster from the lower arch-bar, upwardly tapering friction liners for the inner faces of the columns, friction shoes carried by the bolster and crossing the openings in the side walls of the bolster, a pair of springs urging the shoes against the liners, spring seats for the inner ends of the last-named springs, and a wedge-shaped and longitudinally adjustable spreading element interposed between the seats.
- 65 6. In a railway truck, in combination, a side frame having a lower arch bar and columns rising therefrom, a hollow bolster vertically movable between the columns and having open sides, springs supporting the bolster from the lower arch-bar, upwardly tapering friction liners for the inner faces of the columns, friction shoes carried by the bolster and crossing the openings in the side walls of the bolster, a pair of springs urging the shoes against the liners, spring seats for the inner ends of the last-named springs, and an oscillatable spreading element interposed between the seats.
- 70 7. In a railway truck, in combination, a side frame having a lower arch bar and columns rising therefrom, a hollow bolster vertically movable between the columns and having open sides, springs supporting the bolster from the lower arch bar, upwardly tapering friction liners for the inner faces of the columns, friction shoes carried by the bolster and crossing the openings in the side walls of the bolster, a pair of springs urging the shoes against the liners, spring seats for the inner ends of the last-named springs, and a wedge-shaped and longitudinally adjustable spreading element interposed between the seats.
- 75 8. In a railway truck, in combination, a side frame having top and bottom bars and a pair of relatively spaced vertical columns connecting the bars, the upper portions of opposing faces of the columns being offset toward each other, a bolster located between the columns and being laterally open and vertically channeled to receive the offset portions thereof, upwardly tapering wear plates seated against such offset portions, wear plates carried by the bolster and crossing the lateral openings and engaging the tapered plates, springs housed within the bolster and urging the last defined wear plates outward, and supporting springs for the bolster carried by the bottom bar.
- 80 9. In a railway truck, in combination, a side frame having a lower arch bar and guide columns rising therefrom, a spring-supported bolster vertically movable between the columns, friction shoes carried by the bolster, spring means for advancing said shoes for exerting lateral pressure on the columns for frictionally resisting the vertical movement of the bolster, and means including at least one stationary wedge member associated with said frame for augmenting such pressure by compressing said spring means as the bolster descends.
- 85 10. In a railway truck, in combination, a side frame comprising a tension member, a compression member, and spaced vertical columns connecting said members, a truck bolster having an

end located between said columns, springs supporting said bolster from said side frame, friction plates mounted on opposing faces of said columns and presenting opposed downwardly converging surfaces, friction shoes associated with said bolster end and slidably supported thereby for reciprocable motion laterally of said bolster, surfaces on said shoes adapted to engage said downwardly converging surfaces, and springs chambered within said bolster end for urging said shoes into continuous frictional engagement with said downwardly converging surfaces.

5 11. In a railway truck, a side frame member, a bolster member, bolster member supporting springs beneath said bolster member for supporting the latter from said side frame member, a friction element movable with said side frame member and having a vertical friction surface, a wedge element, and means having wedging and 15 friction surfaces engaging said friction element and wedge element for frictionally dampening the vertical vibrations of said springs, said means including a spring in addition to said bolster member supporting springs for holding the parts

10 in frictional contact, said means having at least a portion thereof movable with one of said members and said wedge element being movable with the other of said members.

12. In a railway truck, a side frame member, a bolster member having a portion rectangular in cross-section, bolster member supporting springs beneath said portion of the bolster member for supporting the bolster member from said side frame member, a friction element movable 10 with said side frame member and having a vertical frictional surface, a wedge element separate from the bolster, and means having wedging and friction surfaces engaging said friction element and wedge element for frictionally dampening the vertical vibrations of said springs, said means including a spring in addition to said bolster member supporting springs for holding the parts in frictional contact, said means having at least a portion thereof movable with one of said members and said wedge element being movable 15 with the other of said members.
